UNITED STATES PATENT OFFICE.

FRANCIS LIVINGSTONE BALL, OF NOTTINGHAM, ENGLAND.

APPARATUS FOR WINDING YARN AND THE LIKE.

Application filed September 26, 1921. Serial No. 503,437.

To all whom it may concern:

Be it known that I, FRANCIS LIVINGSTONE BALL, a subject of the King of Great Britain, residing at No. 109 Forest Road, Nottingham, England, have invented Improvements in and Relating to Apparatus for Winding Yarn and the like, of which the following is a specification.

This invention has reference to improvements in and relating to apparatus for winding yarn and the like and has particular reference to the type wherein the thread control mechanism or thread guides are carried by a rod or traverse bar adapted to be reciprocated from a cam shaft.

The object of the present invention is the provision of means for producing a balanced effort on the main or cam shaft, means for decreasing the wear of the gearing actuating said shaft, means for equalizing the resistance to rotation of said shaft during the whole of each revolution, and improvements in the means for and in the method of actuating the winding mechanism.

The principal feature of this invention consists in dividing the traverse bar into independent lengths and actuating such lengths by sets of cams placed out of phase with one another on the cam shaft.

In order that this invention may be more fully understood reference will now be made to the accompanying drawing, wherein:

Fig. 1 is a part front elevation of a winding machine constructed according to the present invention,

Fig. 2 is an end view thereof,

Fig. 3 is a view showing the relative disposition of the cams, and

Fig. 4 is a detail view of one type of rocking lever.

The machine as shown herewith comprises a frame 1, carrying independent spindles 2 upon which the yarn 3 to be wound is mounted. Such yarn passes through suitable tensioning mechanism 4 to the control mechanism 5 carried by control rods 6, and from thence to the bobbins 7 mounted upon independent rotating spindles 8. Also each rod 6 carries complete control mechanism 5 of any usual and convenient type.

Rotary motion is imparted to the driving shaft 9 from any convenient source there being provided fast and loose pulleys 10 and 11 respectively and a fork 12 if and when a belt drive is employed. Pulleys 13 on the shaft 9 impart rotary motion to the spindles

8 through the medium of pulleys 14 mounted upon such spindles and belts or bands 15. A pulley 16 on the shaft 9 imparts rotary motion to a pulley 17 carried by a countershaft 18 by means of a belt 19 and said countershaft carries a toothed pinion 20 in mesh with a toothed wheel 21 on a second countershaft 22. Coaxial with the wheel 21 is a pinion 23 engaging a toothed wheel 24 mounted upon the cam shaft 25, such shaft extending longitudinally the length of the machine. Further in conjunction with the thread tensioning mechanism the cam shaft imparts rotary motion to a roller 26 by means of a belt and pulleys as indicated at 27.

The various elements as above described are constructed and arranged in accordance with present practice and no claim is made thereto and this invention is not limited to the application to a machine provided with such elements excepting as aforesaid.

According to present practice all of the rods 6 are carried by one and the same traverse bar, reciprocatory motion being imparted thereto from one or more cams mounted in phase upon the cam shaft 25.

In the carrying into effect of the present invention the traverse bar is divided into independent lengths and for the purpose of description the bar as shown herewith is divided into three lengths 28^a, 28^b and 28^c but it will be understood that the bar may be otherwise conveniently divided. Each length 28^a, 28^b and 28^c carries a certain proportion of the control rods 6 and such lengths are independently actuated by guided reciprocating members or traverse bar actuating rods 6^a from sets of cams 29^a, 29^b and 29^c mounted upon the cam shaft 25, there being the same number of sets of cams as there are lengths of traverse bar.

For the production of a balanced effort, which is the main object of this invention, the sets of cams 29^a, 29^b and 29^c are placed out of phase with one another although the cams within each set are in phase. The action of certain sets of the cams is thus opposed to the action of the other sets and while certain of the cams and lengths of traverse bar actuated thereby are rising the other sets of cams and corresponding lengths of traverse bar are falling.

In one arrangement which is illustrated herewith the cams are so designed that the fall thereof is twice as steep as the rise.

Consequently if three sets of cams are employed and the traverse bar divided into three equal lengths, each length being actuated by one set and such sets arranged out of phase so that while one set is falling the other two sets are rising, then the torque produced on the cam shaft by the first set will be opposed and equal to the torque produced on said shaft by the second set. The 10 resistance to rotation of the cam shaft will then approach equality throughout the whole of each revolution.

Whatever design of cam is employed the above object may be readily attained by 15 suitably modifying the angle of phase difference between the sets of cams and the number of lengths into which the traverse bar is divided, the aforementioned design being submitted merely as an example. 20 Also in each set of cams there may be any convenient number of cams depending upon the individual requirements of each machine.

Levers 30 pivoted to the standard at 31 25 carry rollers 32 bearing on the respective cams 29, there being one lever 30 to each cam, and at their extremity remote from the pivot such levers carry rollers 33 bearing on the lower extremities of the rods 6^a, means being preferably provided as indicated for 30 varying the effective lengths of such rods. Fig. 3 illustrates the relative disposition of the pairs of cams 29^a, 29^b and 29^c with respect to one another, the position of the 35 cams as shown in this figure corresponding to the position of the bars 28^a, 28^b, 28^c shown in Fig. 1.

The levers 30 are preferably of the type 40 illustrated in Fig. 4, which as shown comprises parallel and similar side members 30^a and 30^b, between which are accommodated the rollers 32 and 33, positioned upon shanked screw bearings 35 by nuts 36. Said type of lever is readily interchangeable and

renewed and the strain produced in the retaining members thereof is balanced particularly as opposed to the type at present used wherein only one side member is employed.

As will be readily understood by reason of actuating a winding engine in the improved manner as herein described the resistance to rotation of the cam shaft during the whole of each revolution is practically constant, a balanced effort is obtained, the running of the machine is sweeter and more even, and less power is required whilst the wear on the gear is materially reduced.

I claim:—

1. An apparatus for winding yarn comprising a traverse thread guide bar divided into independent lengths, a set of cams for actuating each length and each set of cams being of similar and unequal sided cams in phase so designed and positioned that the steepness of the rise is to the steepness of the fall of each cam as the number of sets of cams falling is to the number of sets of cams rising.

2. An apparatus for winding yarn comprising a frame, a sectional traverse thread guide bar, a lever having one end pivotally connected to said frame, rollers arranged in the opposite ends of said levers and adapted to bear on the lower ends of the spindles of said bar, intermediate rollers carried by said levers, a cam shaft, the cams of said shaft being adapted to contact said intermediate rollers and arranged in sets, each set of cams corresponding to the number of sections of said bar, and the cams of one set being placed out of phase with the cams of the other sets whereby a balancing effort is produced on said cam shaft.

FRANCIS LIVINGSTONE BALL.
